DESIGN FOR A RECTANGULAR CONTAINER FOR FROZEN PRODUCTS

Louis A. M. Phelan, Beloit, Wis.

Application May 11, 1942, Serial No. 106,859

Term of patent 14 years

(CL. D58—17)

To all whom it may concern:

Be it known that I, Louis A. M. Phelan, a citizen of the United States, residing at Beloit, in the county of Rock and State of Wisconsin, have invented a new, original, and ornamental Design for Rectangular Containers for Frozen Products, of which the following is a specification, reference being had to the accompanying drawing, forming a part thereof.

Fig. 1 is a wide side elevational view of a rectangular container for frozen products showing my new design.

Fig. 2 is a narrow side elevational view thereof. Fig. 3 is a bottom view of my new design. The characteristic features of my design reside in a rectangular container of the specific dimensional proportions shown having rounded corners and diagonally located lifting lugs disposed and arranged specifically as illustrated.

I claim:

The ornamental design for a rectangular container for frozen products, as shown, and described.

LOUIS A. M. PHELAN.
